UNITED STATES PATENT OFFICE

EDWIN O. BENNETT, OF PONCA CITY, OKLAHOMA, ASSIGNOR TO CONTINENTAL OIL COMPANY, OF PONCA CITY, OKLAHOMA, A CORPORATION OF DELAWARE

DRY ICE CONVERSION UNIT

Application filed October 31, 1931. Serial No. 572,245.

My invention relates to a dry ice conversion unit and more particularly to a container for dry ice (solid CO_2) so that it may be used as a refrigerant in an ordinary water-ice box.

Inasmuch as the temperatures produced by dry ice are extremely low, dry ice cannot be used in ordinary ice boxes as a substitute for water-ice, because the combustibles in the ice box will become frozen solid. The temperature of dry ice is about 110° below zero F.

One pound of dry ice will produce the same refrigerating effect as 14 pounds of water-ice. That is, dry ice is about fourteen times as efficient as water-ice, as a refrigerant. Accordingly, it is obvious that a small block of dry ice will be the equivalent of a large block of water-ice.

One object of my invention is to provide a unit which will enable dry ice to be used as a refrigerant in the ordinary water-ice box.

Another object of my invention is to provide a unit whereby dry ice may be used without freezing of the combustibles in the ice box.

A further object of my invention is to provide a refrigerating effect control so that the temperature in the ice box may be controlled.

Still another object of my invention is to provide means for freezing water into cubes of water-ice so water-ice may be available for cooling drinks and other purposes.

A still further object of my invention is to provide a vent which will preclude pressure being built up during the sublimation process of the CO_2 from the solid to the gaseous state, due to the absorption of heat by the dry ice.

Figure 1 shows a front elevation of an ice box equipped with one embodiment of my invention.

Figure 2 shows a section taken on Figure 1 along the line 2—2.

Figure 3 shows a sectional view of a device embodying my invention, showing control means for governing the temperature of the refrigerator.

Figure 4 is a sectional view taken on the line 4—4 of Figure 3.

Figure 5 is a perspective view of the conversion unit, showing the control means.

Figure 6 is a perspective view showing another type of control means.

In general my invention contemplates a heat insulated unit suitably partitioned to provide an upper chamber for the reception of a quantity of dry ice. Below the dry ice chamber are positioned a plurality of trays for the reception of water to be frozen into water-ice. The upper and lower surfaces of the unit are provided with a plurality of openings through which air circulation takes place. These holes are provided with any suitably constructed control means so that the area through which air circulation takes place may be varied. Means are provided for controlling this area through the control means either manually or automatically.

More particularly referring now to the drawings, the dry ice container 1 is mounted in any suitable fashion in a normal ice chamber of a common water-ice box 2. The walls of the container 1 are made of any suitable heat insulation construction. A partition 3 divides the container into an upper chamber 4 provided with a door 5 for the insertion of a block of dry ice 6. The partition 3 is provided with perforations to allow circulation to take place. The lower chamber of the container 7 is provided with two water-ice trays 8. A vent 9 precludes the building up of pressure due to the sublimation of the dry ice from the solid to the gaseous state. The vent 9 may be provided with a valve arrangement 10 which may be hingedly mounted so that it will open upon the slightest pressure. A suitable baffle 13 may be provided at the interior orifice of vent 9 to prevent the drawing in of any warm air due to the circulation of the cooled air within the box. A series of openings 11 are provided in the upper wall of my container. The lower walls of my container are provided with a series of openings 12'. These openings 12' are provided with shutters or other suitable

100

control means to vary the amount of opening. The shutter or shutters may be manually controlled or thermostatically controlled by any suitable mechanical or electrical thermostatic device. The operating means for the cooling control is diagrammatically shown at 12 and may be positioned in any suitable location.

In operation my unit is installed in an ordinary water-ice box and a piece of dry ice is placed in the upper chamber of my unit. The arrows in Figure 1 indicate the circulation through my ice box. As the air is cooled, it becomes more dense and passes downwardly through the lower holes 12 and over the comestibles in the ice box, cooling them. Having absorbed some of the heat from the comestibles present, the air will become lighter and rise and pass downwardly through the refrigerant container. It is obvious that the size of the openings or the number of openings will govern the cooling effect and accordingly the temperature within the ice box.

Water-ice may be frozen in the trays and thus can be used for beverage and other household purposes. The vent will prevent the building up of any undesirable pressure. There is no necessity of fitting drains as is the case in an ordinary ice box. The temperature control will prevent undue dissipation of the dry ice and it will last a surprising length of time. There are no moving parts to get out of order. No defrosting, as is the case with mechanical refrigerators is necessary. The dry ice need only be replenished at more or less infrequent intervals depending upon how much demand is made upon the refrigerant.

The switch member 12, when rotated, will rotate rod 20 which carries a worm 21. Suitably mounted within the refrigerator upon supports 22 and 23 is a rod 24 which carries a segment of a gear 25. The segment 25 is keyed to rod 24. Also keyed to rod 24 are levers 26 and 27 provided with slots 28 and 29 which engage pintles 30 and 31. The pintles are mounted in shutter members 32 and 33 which are disposed to slide in guide members 34. The shutter members 32 are provided with openings 35 which are spaced in the same relationship as the openings 11 and 12. As the shaft 20 is rotated, the arrangement will reciprocate the shutters 32 to positions which vary the effective area through which the circulation of refrigerant gas takes place. The linkage in Figure 6 is a modification which may be employed, in which shaft 20 carries a lever 40 which is connected to links 42 and 43 by means of links 41. Bell crank levers 44 and 45 are mounted upon suitable brackets 46 and 47. The bell crank levers have slotted ends 48 and 49 which engage pintles 30 and 31 of

the shutter members 32 and 33 as in the previous modification.

It is obvious that I have provided a means for employing dry ice which will enable it to be used as a refrigerant having substantially all of the advantages of the mechanical refrigerator and none of its disadvantages. Then, too, it is obvious that all of the advantages of a water-ice box are retained with none of its disadvantages present. With dry ice there is none of the undesirable dehydration of the comestibles which takes place in a mechanical refrigerator.

Though I have described a unit which may be used for the conversion of a water-ice box, it is manifest that my invention may be embodied in an ice box during manufacture, where designed especially for dry ice alone.

With the conversion unit, however, it is a simple matter in the event that a supply of dry ice becomes inaccessible that the ice box can be again used as an ordinary water-ice box without great difficulty.

It is to be understood that my invention is not to be limited to the specific details shown and described except in so far as expressed in my claims.

I claim as my invention:

1. A conversion unit adapted to modify a water-ice box for use with dry ice comprising, a container having heat insulated walls, a perforated partition in said container dividing it into upper and lower chambers, said partition being adapted to support a piece of dry ice, a tray adapted to contain water to be frozen slidably positioned below said partition within said lower chamber, a plurality of openings in said container adapted to permit a circulation of ice box air through said container, and means to vary the effective area of said openings.

2. A conversion unit adapted to modify a water-ice box for use with dry ice comprising, a container having heat insulated walls, a perforated partition in said container dividing it into upper and lower chambers, said partition being adapted to support a piece of dry ice, a tray adapted to contain water to be frozen slidably positioned below said partition within said lower chamber, a plurality of openings in said container adapted to permit a circulation of ice box air through said container, means to vary the effective area of said openings, and means to control said means.

3. An ice box including the combination of a container having heat insulated walls, a perforated partition in said container dividing it into upper and lower chambers, said partition being adapted to support a piece of dry ice, a tray adapted to contain water to be frozen slidably positioned below said partition within said lower chamber, a plurality of openings in said container

adapted to permit a circulation of ice box air through said container, and means to vary the effective area of said openings.

4. An ice box including the combination 5 of a container having heat insulated walls, a perforated partition in said container dividing it into upper and lower chambers, said partition being adapted to support a piece of dry ice, a tray adapted to contain 10 water to be frozen slidably positioned below said partition within said lower chamber, a plurality of openings in said container adapted to permit a circulation of ice box air through said container, means to vary the 15 effective area of said openings, and means to control said means.

In testimony whereof I affix my signature.

EDWIN O. BENNETT.
